STERILIZING VAULT

Thomas D. Ross, Dallas, Tex.

Application May 11, 1942, Serial No. 442,461

6 Claims. (Cl. 21—96)

This invention relates to new and useful improvements in sterilizing vaults.

This application is filed as a continuation-in-part of my co-pending application, Serial No. 315,540, filed January 25, 1940.

One object of the invention is to provide an improved sterilizing vault which is adapted to receive and sterilize articles of various sizes, such as mattresses, furniture and the like and which is so constructed that the articles may be conveniently and readily inserted and removed therefrom.

An important object of the invention is to provide a sterilizing vault comprising an enlarged unobstructed chamber through which heated air for effecting sterilization of articles within said chamber, is circulated, together with a unitary rack which is movable into and out of said chamber and which is entirely self supporting, whereby rails or other supports for said rack within the chamber are obviated; the arrangement facilitating the sterilizing of various types of articles since the rack may be positioned within the chamber and may support certain articles, or said rack may be withdrawn from the chamber and the unobstructed chamber utilized to receive other and larger articles, such as furniture.

A further object of the invention is to provide an improved vault, of the character described, wherein the unitary rack is arranged to co-act with the opening in the sterilizing chamber, through which the rack is insertable, such co-action effecting a seal at the opening when the rack is within the chamber and also when said rack is withdrawn or in an extended position outside of said chamber, whereby heat losses from within the chamber when the rack is either within or outside of the chamber, are minimized.

Another object of the invention is to provide an improved sterilizing vault, of the character described, wherein heated air is constantly circulated through the sterilizing chamber so as to intimately contact and sterilize the articles therein, said vault lending itself to any suitable heating apparatus for heating the air and also being so constructed that the heating unit may be disposed in any desirable location adjacent thereto.

A still further object of the invention is to provide a sterilizing apparatus, wherein the unitary self-supporting rack is formed with enlarged end walls or plates which engage the marginal portions of the opening through which the rack is slidable and which function, not only to seal the opening when the rack is en-

tirely within or fully extended from the chamber, but also act as stops to limit the sliding movement of said rack.

A particular object of the invention is to provide an improved vault, of the character described, which is prefabricated in sections, whereby shipment and storage of the vault is facilitated, the sections being readily assembled at the location where the device is to be used by unskilled labor and in a minimum amount of time.

A construction designed to carry out the invention will be hereinafter described together with other features of the invention.

15 The invention will be more readily understood from a reading of the following specification and by reference to the accompanying drawings, wherein an example of the invention is shown and wherein:

20 Figure 1 is an isometric view of a sterilizing vault, constructed in accordance with the invention.

25 Figure 2 is an enlarged, horizontal, cross-sectional view of the vault with the rack disposed therein.

Figure 3 is a longitudinal vertical sectional view, taken on the line 3—3 of Figure 2, with the rack in an extended position.

30 Figure 4 is a reduced, transverse vertical sectional view, illustrating the air inlet and outlet openings in the chamber.

Figure 5 is an isometric view of the rack.

Figure 6 is an enlarged, sectional detail view of a portion of one of the end panels of the rack, showing the seal between the panel and the casing of the vault.

35 Figure 7 is a view, partly in section and partly in elevation, of a modified form of the invention, and

40 Figure 8 is a horizontal, cross-sectional view of the modification shown in Figure 7.

In the drawings, the numeral 10 designates a casing or cabinet which is constructed of side wall sections 11 and 12, end wall sections 13 and 45 14, a top section 15 and a bottom section 16. Each section is individually fabricated and includes spaced walls having heat insulating material 17 therebetween. The sections are assembled to form the casing or cabinet and are secured to each other by any suitable means, such as angle bars 18 which are located at the corners formed by the meeting sections. The interior of the cabinet or casing formed by the various sections is entirely unobstructed and forms a sterilizing chamber A.

The end wall 14 of the casing is provided with a rectangular opening 19 through which a unitary rack B is slidable. The rack is clearly shown in Figure 5 and includes an inner end wall or plate 20 and an outer end wall or plate 21, these walls being constructed of a wooden frame work 22 covered by metallic sheets 23, as is clearly shown in Figure 6. Suitable insulating material 24 may be disposed between the metallic sheets of the end plates. Each end plate is formed with an outwardly projecting peripheral flange 25 and this flange is adapted to abut the wall section 14 around the opening 19; in other words, the flange portion 25 of each end plate 20 and 21 is of greater area than the opening 19.

The end plates 20 and 21 are connected to each other by longitudinally extending angle members or bars 26 which have their ends secured to vertical angle members 27, the latter being fastened to the inner surface of the end plates 20 and 21. The longitudinal angle members 26 are adapted to support transverse bars or slats 28 which extend between said members and which are adapted to support mattresses, or other articles to be sterilized. The rack B which is formed in the manner above described is supported by rollers 29 which are disposed at the corners of the rack, each roller being mounted within an offset casting 30 secured to the outer surface of the end plates 20 and 21.

The rack B is slidable through the opening 19 in the end wall 14 of the casing and the rollers 29 which are secured to the inner end plate 20 of said rack ride upon flanged tracks 31 which are mounted within the casing on the bottom section 16 of said casing (Figure 4). The rollers 29 which are secured to the outer end plate 21 of the rack are slidable upon similar tracks 32 which are supported upon a suitable framework 33 disposed outside of the casing. The tracks 31 and 32 are in alignment with each other and in effect form a single continuous trackway for guiding the sliding movement of the rack. It is pointed out that if desired, the rails 31 and 32 may be continuous and may extend through the lower portion of the opening 19, whereby the separate tracks, as illustrated, would be eliminated.

When the rack B is in its inner position within the interior of the casing, as shown in Figure 2, the peripheral flange 25 of the outer end plate 21 of said rack engages the front wall of the end section 14 around the opening 19. A suitable packing material 34, such as felt may be secured to the section 14 so as to be engaged by the flange 25 of the plate 21, whereby a positive seal will be effected at this point (Fig. 6). Thus, when the rack is in its inner position within the sterilizing chamber A, the outer end plate 21 seals the opening 19 to prevent the escape of heat from said chamber. Suitable latches 35 are provided on the section 14 and the end plate 21 to lock the rack in its inner position within the sterilizing chamber.

When the rack is withdrawn from the chamber A and is moved outwardly along the rails 32, the inner end plate 20 of the rack B will strike the inner surface of the end wall section 14 and its flange 25 will coat with the wall to seal the opening 19, as is clearly shown in Figure 3. The provision of the flange 25 also provides a stop, whereby the rack B cannot be completely withdrawn from the casing 10. Although it is desirable that the inner plate 20 be utilized to seal the opening 19 when the rack is in its outer position, it is not essential that this be done in order to carry out the invention. It would be possible to eliminate the flange 25 on the inner plate 20 and to com-

pletely withdraw the rack B from said casing. In such instance, a door (not shown) would be utilized to close the opening 19 when the rack B is withdrawn therefrom.

5 The sterilizing chamber A may be heated in any suitable manner but it is preferable to employ hot air. The heated air is introduced through an air inlet opening 36 which is formed in the upper portion of the wall section 12 and this air circulates across and downwardly of the interior of the chamber, the downward movement of the air being aided by a curved baffle 37 which extends longitudinally of the chamber at the corner formed by the intersection of the wall 11 and the top 15 (Figure 4). The circulating air then escapes from the interior of the chamber through an air outlet 38 which is located in the wall 12 below the air inlet 36, as is clearly shown in Figure 3. It is preferable that the same air be constantly re-circulated through the chamber and to effect the re-circulation of such air, a heating unit 39 of any desired construction is mounted exteriorly of the casing 10. The lower portion of the unit 39 communicates through a flue 40 with the air outlet opening 38, while the upper end of said unit communicates through a similar flue 41 with the air inlet opening 36. A blower 42 is disposed in the flue 41 and is driven by an electric motor 43, or other means which is supported upon a bracket 44 secured to the exterior surface of the wall 12 adjacent the heating unit 39. In this manner, air is heated by the unit 39 and is then forced into the upper portion of the chamber A, circulates downwardly through the chamber and escapes back to the heating unit through the air outlet opening 38, from which point it is again re-circulated. Although it is desirable that the heating unit be disposed adjacent to the casing 10, it is not essential for said unit could be mounted at some remote point and connected to the inlet 36 and outlet 38 by elongate ducts, flues or other conductors. Also, it is pointed out that the air inlet and outlet openings may be provided in any of the wall sections, other than the side wall 12.

45 When the rack B is within the chamber A, it substantially fills said chamber and the rack is adapted to support various articles to be sterilized. The rack provides a plurality of shelves for receiving articles, such as mattresses, linens and the like. Of course, it is possible to remove all of the transverse slats or bars 28 except the lowermost slats, in which case the rack would form a box-like structure for the reception of larger articles. However, the 50 particular article which could be received within the rack is limited by the size of said rack and larger pieces, such as chairs or couches or other pieces of furniture could not be sterilized within the rack because of their size. In such case, the rack is completely withdrawn from the 55 sterilizing chamber A, being moved to the position shown in Figure 3, whereby the inner end plate 20 of the rack seals the opening 19. The interior of the casing then forms a large unobstructed chamber A and to permit the insertion of large articles to be sterilized within this chamber, the side wall 12 is formed with an access opening 45 which is normally closed by an insulated hinged door 46. When the rack B is 60 moved to an extended position, the door 46 may be opened and large articles, such as furniture, may be readily inserted into the interior of the casing and may be efficiently sterilized within the chamber A. Thus, the device provides a 65 sterilizing apparatus which is capable of accom-

70 75

modating any type of article which requires sterilization. The rack B is adapted to support any of the smaller articles, while the provision of the large door 46 permits access to the chamber A when the rack is in an extended position, whereby the larger articles may be readily inserted and removed therefrom. It is pointed out that although the door 46 has been illustrated as disposed in the wall 12 of the casing, said door could be mounted either in the opposite side wall 11 or in the end wall 13 of the said casing.

In Figures 7 and 8, a slightly modified form of the invention is shown. In this case, elongate supporting rails 33a, having flanged guide tracks 32a mounted thereon are provided. A casing 10a which is similar in construction to the casing 10 is mounted on the inner portion of the rails 33a and is provided with an opening 19a in one end wall. The rack B which is constructed in substantially the same manner as the rack of the first form is slideable through the opening 19a, being supported upon the guide rails 32a. A side access opening 45a is formed in the casing 10a and this opening is normally closed by a door 46a. The rear end wall of the casing 10a forms the front wall of a heating unit 50 which has an oil burner type of heater 51 disposed therein. An air outlet opening 38a is formed in the rear end wall of the casing 10a and communicates with the interior of the heating unit casing 50, whereby air is withdrawn from the sterilizing chamber. The upper end of the heating unit casing 50 communicates with the interior of the sterilizing chamber through an air inlet opening 36a which has a suitable flue 52 mounted therein. A fan 53 is mounted within the flue 52 and is driven by a pulley 54 which is secured to the outer end of the fan shaft 55. A deflecting baffle 56 is disposed within the sterilizing chamber adjacent the air inlet opening 36a and serves to deflect the air forced into the chamber upwardly toward the top of the chamber.

It will be obvious that the form shown in Figures 7 and 8 operates in substantially the same way as the first form of the invention. Although not illustrated, the walls of the casing 10a may be suitably insulated in any desired manner. The end plates of the rack B co-act with the opening 19a of the casing to seal said opening when the rack is in its innermost position within the sterilizing chamber and also when the rack is withdrawn and is disposed in its extended position. The rails, as well as the guide tracks 32a of this form are continuous and extend throughout the length of the casing 10a and also beyond the end wall of said casing to accommodate the rack when in its extended position. In both forms of the invention a suitable thermometer 57 may be mounted at some point on the exterior surface of the casing so as to indicate the temperature of the air within the sterilizing chamber A.

I claim:

1. A device of the class described comprising a vault, rails supporting the vault, the front wall of the vault having an opening therein, a rack including end plates, said plates being of greater area than said opening, bars rigidly connecting said plates, said plates being adapted to alternately engage the opposite sides of the front wall upon moving the rack in said opening, a heat confining chamber, one wall of the vault forming the front wall of the chamber and having upper 75

and lower openings therein affording communication between the vault and chamber, a tubular duct in the upper opening, a fan in the duct, a baffle plate adjacent the duct to force heated air from the duct upwardly in the vault upon operation of the fan, said fan serving to draw air from the vault into the chamber and force the same from the duct, means for heating air in the chamber during circulation thereof, and rollers carried by the rack for engaging the rails.

2. A sterilizing apparatus including, a casing having an opening in one wall thereof, a unitary self-supporting rack for receiving articles to be sterilized slideable through said opening whereby said rack may be disposed entirely within the casing or may be withdrawn therefrom, and means for closing the opening when the rack is withdrawn from the casing, a heating unit communicating with the interior of said casing through an air inlet in the upper portion of one wall and an air outlet in the lower portion of the casing wall, and a baffle disposed within the casing opposite the inlet for directing the hot air from the heating unit downwardly into the interior of said casing.

3. A sterilizing apparatus including, a casing having an opening in one wall thereof and having its interior entirely unobstructed, means for heating the interior of the casing, spaced rails mounted on the floor of said casing, aligned rails disposed externally of said casing beyond the opening in the wall of the casing, a unitary self-supporting rack movable into and out of the interior of the casing, the rack being of a size to substantially fill the interior of said casing when disposed therein and having supporting shelves for receiving articles to be sterilized, the interior of the casing providing a large unobstructed sterilizing chamber for receiving other articles when said rack is withdrawn from the casing, the inner end of the rack being utilized to seal the opening when said rack is withdrawn from the interior of said casing, and rail engaging means carried by the ends of the rack for slidably supporting the same, the rail engaging means being mounted on the external surfaces of said ends so as to be disposed externally of said rack, whereby the inner means engage the interior rails and the outer means engage the external rails.

4. A vault of the class described having an opening in one end wall thereof, a rack slideable in the opening and including end plates of greater area than that of the opening for closing the opening when the rack is extended from the vault or confined therein, spaced rails on the floor of the vault, aligned rails disposed externally of said vault beyond said opening, and rollers mounted on the exterior of each end plate for engaging the rails to slidably support the rack thereupon, the inner rollers engaging the internal rails and the outer rollers engaging the external rails so that neither of said rollers pass through the opening upon movement of said rack.

5. A vault as set forth in claim 4 wherein the lower end of the opening is disposed above the upper surfaces of the rails so as to prevent the rollers from passing through said opening.

6. A vault as set forth in claim 4 wherein the rollers are offset downwardly relative to the end plates so as to be disposed in a plane below the lower ends of said plates, whereby the plates need close only the opening.
